(57) **CLAIM**

The ornamental design for a laryngoscope, as shown and described.

DESCRIPTION

FIG. 1 is a perspective view of the new ornamental design for a laryngoscope in an open position;

FIG. 2 is a front view of the laryngoscope in the open position;

FIG. 3 is a rear view of the laryngoscope in the open position;

FIG. 4 is a right view of the laryngoscope in the open position;

FIG. 5 is a left view of the laryngoscope in the open position;

FIG. 6 is a top view of the laryngoscope in the open position; and,

FIG. 7 is a bottom view of the laryngoscope in the open position.

The broken lines in FIGS. 1 and 4-6 represent unclaimed environment only, which forms no part of the claimed design.
